UNITED STATES PATENT OFFICE

MORRIS M. RAYMER, OF CHARLTON TOWNSHIP, KALAMAZOO COUNTY, AND RICHARD S. POOLE, OF BATTLE CREEK, MICHIGAN, ASSIGNEES TO KELLOGG COMPANY, OF BATTLE CREEK, MICHIGAN, A CORPORATION OF DELAWARE

PACKING MACHINE

Application filed July 7, 1928. Serial No. 291,005.

The invention relates to packing machines, and has for its object to provide a novel machine constructed and arranged to facilitate the packing of units of material, such as shredded whole wheat biscuits, in an orderly fashion within cartons, wrappers, and other containers, and to provide for the mechanical packing in a simple and reliable manner of bulk material in suitable enveloping material. Other more specific objects of the invention will appear from the description hereinafter and the features of novelty will be pointed out in the claims.

In the accompanying drawings, which illustrate an example of the invention without defining its limits, Fig. 1 is side elevation of one end portion of the novel machine; Fig. 2 is a similar view of the other end portion thereof; Fig. 3 is a plan of one end portion of the machine; Fig. 4 is a similar view of an intermediate section thereof; Fig. 5 is a corresponding view of the other end portion of said machine; Fig. 6 is an end view looking at the right hand end of Fig. 1; Fig. 7 is an opposite end view looking at the left hand end of Fig. 2; Fig. 8 is a side elevation of Fig. 5 looking in a direction opposite to that of Fig. 2; Fig. 9 is a corresponding view looking in a direction opposite to that of Fig. 1; Fig. 10 is a cross-section on the line 10—10 of Fig. 2; Fig. 11 is a fragmentary section on the line 11—11 of Fig. 2; Fig. 12 is a detail section on the line 12—12 of Fig. 9; Fig. 13 is a fragmentary side view of Fig. 12; Fig. 14 is a detail cross-section on the line 14—14 of Fig. 13; Figs. 15 and 16 are detail views, looking at right angles to each other, of gluing means included in the machine; Fig. 17 is a detail view of folding mechanism which forms part of the machine; Figs. 18, 19, 20 and 21 are diagrammatic views illustrating successive steps in the operation of the folding mechanism, and Fig. 22 is a detail section on the line 22—22 of Fig. 17.

For the purpose of illustration and description, and for no other reason, the machine is shown in the accompanying drawings and described hereinafter in a form adapted particularly for the packing of units, such as shredded whole wheat biscuits, it being un-

derstood that the mechanical and other features which constitute the essence of the invention, are equally well adapted for the mechanical packaging of bulk materials. In all of the forms, the machine consists primarily of a series of receptacles, suitable for receiving the food or other material to be packed, said receptacles being mounted on a travelling carrier whereby they are carried from one end of the machine to the other in a continuously recurring cycle of operations. After being filled, the receptacles are arranged to receive the cartons or other containers in which the material is ultimately to be contained, and are then inverted and brought into operative combination with ejecting means whereby the material is discharged from the receptacles into said cartons or other containers coincidentally with the removal of the latter from the receptacles, these latter steps taking place during the return of the receptacles to their initial positions. In order to simplify the description, the goods being packed will hereinafter be referred to as biscuits, with the understanding that this term and the illustration thereof exemplifies the material, regardless of its character, adapted to be packed.

The machine comprises a supporting frame 25 of suitable construction and dimensions on which a travelling carrier, illustrated in the form of parallel, spaced sprocket chains 26, is mounted in any conventional manner, so that at least the upper run of the carrier travels from one end of the machine to the other in a horizontal plane. The sprocket chains 26, as shown, pass over sprocket wheels 27 secured upon a shaft 28 journaled in suitable bearings at one end of the machine, and over similar sprocket wheels fixed upon a shaft 29 rotatably mounted in suitable bearings at the other end of the machine; the carrier exemplified by the sprocket chains 26, may be operated in any convenient way as will be more fully set forth hereinafter.

A plurality of supporting members 30 are secured at spaced intervals to the chains 26 so as to travel therewith, and preferably are provided with guide projections 31 movable lengthwise of stationary guideways 32 fixed

upon the frame 25 as shown in Figs. 10 and 11. With this arrangement the upper run of the carrier is maintained in a constant path, the same being true in the illustrated example of the machine, of the lower run which thus also travels over a fixed path in a horizontal plane. Each carrying member 30 has mounted thereon a receiving member 33 pivoted at 34 and constructed, as to dimensions and form, in accordance with the material being handled by the machine. In the illustrated example the receiving members 33, which for convenience may be termed pockets, are dimensioned and shaped to accommodate the conventional shredded whole wheat biscuits, and are in the form of elongated trays the outer ends of which are open. The receiving members 33, are arranged in cooperative relation to retaining forms 35 secured upon the supporting members 30 in permanent perpendicular relation thereto; the retaining forms 35 in the illustrated example correspond in shape to the receiving members 33 and are dimensioned to receive the same and in any case are adapted to form with said receiving members 33 tubular receptacles as shown in Fig. 14, the outer ends of which are open as shown in Figs. 3, 4, 5 and 12. The receptacles formed by the combined receiving members 33 and retaining forms 35 preferably correspond in cross-sectional form to the shape of the cartons or other containers in which the material is to be packed, and are dimensioned so as to be capable of telescopically receiving said cartons or other containers as will appear more fully hereinafter. The receiving members or pockets 33 are pivotally movable from vertical closed positions, in which they project into the retaining forms 35, to inclined open positions at predetermined angles for instance, of fifty-three degrees more or less as shown in Fig. 11. With this arrangement a series of pockets 33 and cooperating retaining forms 35 are mounted at spaced intervals upon the sprocket chains 26 to move therewith. Any suitable means may be provided for shifting the pockets 33 to and from their open positions and vice-versa and to maintain them in such positions for the required operative periods. For instance, as shown in Fig. 11 of the drawings, the receiving members or pockets 33 are provided with arms 36 fixed against relative movement upon said pockets at the proper points and having slots 37 adapted to slidably accommodate pins 38 or their equivalent which are carried by control levers 39. The latter are pivoted at 40 for instance upon brackets 41 fixed upon the supporting members 30 and at their free ends are provided with rollers or equivalent devices 42 to engage the pocket opening cam 43 and subsequently the pocket closing cam 44. Preferably the machine includes means whereby the pockets 33, after having been adjusted to their open and closed

positions by the pocket opening and closing cams 43 and 44, are positively maintained in such positions during the operative stages wherein this is desired. For this purpose a stationary rail 45 is suitably mounted on the frame 25 so as to extend lengthwise thereof from a point contiguous to the pocket opening cam 43 into delivery relation to the pocket closing cam 44, said rail 45 being engaged by the rollers 42 which travel lengthwise thereof in the operation of the machine; to facilitate the transfer of the rollers 42 from the pocket opening cam 43 to the rail 45 the latter may include an inclined continuation 45^a extending over the cam 43 in spaced parallel relation therewith. A similar rail 46, which may comprise a continuation of the pocket closing cam 44, is fixed upon the frame 25 for engagement by the rollers 42 to maintain the pockets 33 in their closed positions, said rail 46 including a continuation 46^a curved about the shaft 29 as a centre and extending in the direction of travel of the lower runs of the sprocket chains 26 as shown in Fig. 8. To avoid the possibility that the pockets 33 may not be properly positioned within the retaining forms 35 to telescopically receive the cartons, in the manner to be more clearly set forth hereinafter, the retaining forms 35 with the pockets 33 housed therein are caused to pass between vertical form closing rollers 33^a rotatably mounted in a sub-frame 25^a located upon the frame 25 as shown in Figs. 1 and 11 of the drawings. In addition to the above the machine preferably includes means whereby the pockets 33 are positively maintained in their closed positions during the periods at which coincidental removal of the biscuits *a* or other material and the cartons *b* or other containers from the tubular receptacles formed by the pockets 33 and retaining forms 35 takes place. In the form shown in Fig. 9, this means comprises a stationary rail 47 fixed at the proper place upon the frame 25 in a position to be engaged by the rollers 42 to thereby lock the levers 39 and arms 36, and consequently the pockets 33 against pivotal movement toward their open positions. In order that the transfer of the biscuits *a* from the tubular receptacles formed by the co-acting pockets 33 and retaining forms 35 may be efficiently and positively accomplished without the possibility of interruption, the pockets 33 are preferably fitted with mechanically operated ejecting means of suitable type. In the illustrated example of the machine this ejecting means consists of ejectors 48 in the form of plates of substantially the same size as the interior dimensions of the pockets 33 and preferably inclined relatively to the major walls of said pockets to form acute angles therewith as shown in Fig. 12. These ejectors 48 are carried by slides 49 and, if necessary, are suitably braced by braces 50, 130

said slides 49 being movable lengthwise of slots 51 with which said pockets 33 are provided; in order to facilitate the movements of said slides 49, rollers 52 may be provided thereon for rolling engagement with the inner and outer surfaces of the pockets 33 as clearly illustrated in Figs. 12, 13 and 14. Externally of the pockets 33 the slides 49 carry rollers 53 adapted to travel along a stationary cam 54 fixed upon the frame 25 at the proper place for causing said ejectors 48 to function, and to engage a stationary curved cam 55 constituting a continuation of the cam 54 at one end of the machine as shown in Fig. 9, whereby said ejectors 48 are restored to their initial positions, as will be described more fully further on in the specification.

In machines, such as that of the drawings, which are designed for packing units of material, such as the shredded whole wheat biscuits *a*, to a predetermined number in individual cartons, the most efficient results are obtained by locating a predetermined number of operators at different points of the machines, which points for convenience of description may be referred to as stations, at which chairs 56 of conventional type may be located for the convenience and comfort of operators. In the illustrated example five stations A, B, C, D and E are included at which progressive packing of the biscuits or other units takes place, a sixth station F being located at the proper point of the machine for enabling an operator to place the cartons *b* in position upon the tubular receptacles formed by the pockets 33 and retaining form 35 as will appear more fully hereinafter. In practice the carrier chains 26 are continuously driven throughout a given period of operation to successively carry the pockets 33 and retaining forms 35 to the aforesaid stations in accordance with a predetermined and definite cycle of operations. As previously stated herein, any suitable means may be provided for operating the carrier chains 26 in a manner to accord with the above plan of action. To facilitate the packing of biscuits or other units as in the illustrated example, it is desirable, however, to have the chains 26 or equivalent travelling carrier moving very slowly while the pockets 33 are passing the successive stations A, B, C, D and E in order to permit the biscuits or other units to be placed therein without the need for special haste and to then move very rapidly to transfer the pockets from one of said stations to the next in a minimum period of time. For this purpose the driving means for the chains 26 includes elliptical gears 57 and 58 which mesh with each other and are carried by shafts 59 and 60, journalled in suitable bearings on the frame 25. To rotatably operate these elliptical gears 57 and 58, the shaft 59 carries a pinion 61 which is connected by means of a sprocket chain 62 with a sprocket wheel 63 loosely mounted on a shaft 64 journalled in suitable bearings on the frame 25; an idler sprocket 62^a may be provided for taking up slack in the chain 62 if desired. The sprocket wheel 63 is in fixed connection with a gear 65 to rotate therewith, said gear 65 being also loose upon the shaft 64 and meshing with a clutch gear 66 loosely mounted on a shaft 67 also journalled in suitable bearings on the frame 25. The clutch gear 66 carries a clutch member 68 which is arranged to cooperate with a mating clutch member 69 slidably mounted upon the shaft 67 and fixed to turn therewith; a suitable operating lever 70 pivoted at 71 upon the frame 25 is connected with the clutch member 69 and is adapted to be manually operated to shift the latter into and out of engagement with the clutch member 68 at will. The shaft 67 further has fixed thereon a gear 72 meshing with a pinion 73 secured upon the shaft 64 which in addition carries a sprocket wheel 74 connected by means of a sprocket chain 75 with an electric motor or other source of power, which it has not been deemed necessary to illustrate in the drawings. The operative connection between the driving means above set forth and the carrier chain 26 is effected by means of a pinion 76 fixed upon the shaft 60 and meshing with a gear 77 secured upon the shaft 29 on which the carrier chain sprockets 29 are mounted.

The biscuits *a* or other units to be packed may be supplied to the operators at the stations A, B, C, D and E in any convenient manner. For instance, as shown in the drawings, the biscuits *a* may be delivered in a continuous supply by means of a conveyor belt 78 located in front of the carrier chains 26 with its upper run travelling horizontally in substantially the same plane therewith as shown in Figs. 7 and 10; in the preferred arrangement the supplies of biscuits *a* may be contained in pans P or their equivalent which are carried by the belt 78 to the stations A, B, C, D and E in succession. The conveyor belt 78 is endless and passes over rollers 78^a and 78^b located at opposite ends of the machine, said rollers being mounted respectively upon shafts 79 and 80 journalled in bearings 81 and 82; as shown in Fig. 1, the bearings 81 may be slidably mounted in brackets 83 fixed upon the frame 25 and provided with adjusting screws 84 or equivalent devices for taking up slack in said conveyor belt 78. The bearings 82 are fixed upon the frame 25 and the shaft 80 journalled therein is provided with a sprocket wheel 85 connected by means of a sprocket chain 86 with a cooperating sprocket secured upon the shaft 29 whereby motion is imparted to said conveyor belt 78 in the desired manner. Supporting rollers 87 may be provided as needed for the lower run of the conveyor belt 78, the upper run

thereof being supported against sagging by a rigid supporting frame comprising strips 88 over which it travels.

The cartons *b* in which the biscuits *a* are contained in predetermined number are generally of that class of containers which are constructed from cardboard so as to be foldable from a flat condition to an open condition, in which said carton customarily comprises a body, the opposite ends of which are closed by flaps. For the purpose of efficiency operating with such cartons the illustrated machine is provided with means for closing the bottom end of the containers and for gluing the same. The means as shown in the drawings consists of a tucker 89 fixed upon a shaft 90 rotatably mounted in suitable bearings on the frame 25 and carrying a pinion 91; the latter meshes with a second pinion 92 secured upon a stub shaft 93 journalled on the frame 25 as shown in Figs. 2 and 5. The stub shaft 93 further carries a sprocket pinion 94 connected by means of a sprocket chain 95 with a sprocket wheel 96 secured upon the shaft 30, so that said tucker 89 is operatively connected with the motor or other driving means through the previously described gearing which includes the elliptical gears 57 and 58. A tension sprocket 97 carried by a lever 98 pivoted on the stub shaft 93 may be provided to compensate for any slack in the sprocket chains 95. In addition to the above, the means for closing the bottom ends of the cartons includes a member 99 fixed at one end of the machine and curved about the shaft 29 as a centre, said member 99 serving as a flap retainer in the manner to be more fully set forth hereinafter. The tucker 89 and the flap retaining member 99 serve to successively fold the front flaps *b*1 and rear flaps *b*2, the latter terms being used merely with respect to the position occupied by the cartons and the direction of movement thereof, at the time. Distending members 100 are located in registry with the member 99 upon a crossbar 101 fixed on the frame 25 and are constructed and arranged to distend the side flaps *b*3 of the cartons, as illustrated in Fig. 16, and guide the same, in such distended positions to glue bars 102 suitably mounted in the machine in operative relation to glue rolls 103 carried by the shaft 67 as shown in Figs. 2 and 5. The glue rolls 103 have their peripheral surfaces in glue receiving relation to glue receptacles or pots 104 suitably supported upon the crossbar 101 as shown in Figs. 5, 15 and 16; the glue receptacles 104 may be of any conventional type and if desired may include scrapers 105 capable of being adjusted by means of hand screws 106.

The flap retaining member 99 at its lower or exit end terminates in proximity to opposite acting folding members 107 and 107^a preferably provided at their opposed ends

with rollers 108 and transversely slidable in directions toward and away from each other in stationary guides 109 fixed upon the frame 25 at the proper points. The folding members 107 and 107^a are transversely operated by any suitable mechanism, the latter in the illustrated example comprising bell-crank levers 110 pivoted at 111 upon the frame 25 and in pin and slot connection with said members 107 and 107^a at 112. The bell-crank levers 110 are pivotally connected at 113 with links 114 at one end thereof, the opposite ends of said links being forked as indicated at 115 and slidably straddling upright shafts 116 and 116^a journalled in suitable bearings on the frame 25 as shown in Fig. 7. At their forked ends 115, the links 114 are provided with depending rollers 117 which project into the cam grooves 118 of cams 119 fixed upon the shafts 116 and 116^a, said cams being connected to rotate in unison by means of a belt or chain 120 as shown in Fig. 7. The arrangement of the cam grooves 118 is such that the folding members 107 and 107^a will be inversely reciprocated, so as to perform their folding functions in alternate sequence as will appear more fully hereinafter. Any suitable means may be provided for rotating the cams 119, as for instance by providing the shaft 116 with a bevel gear 121 in mesh with a similar bevel gear 122 fixed upon the shaft 60 as shown in Fig. 7. Suitable stationary folding guides 123 are secured upon the frame 25 in advance of and in proximity to the folding members 107 and 107^a as shown in Fig. 17, said guides 123 serving to function successively to partly fold the side flaps of the cartons inwardly prior to the complete folding thereof by the folding members 107 and 107^a.

The machine of the drawings further includes an endless dryer belt 124 located in receiving relation to the aforesaid folding means and passing over rolls 125 mounted at opposite ends of the machine on shafts 126 journalled in suitable bearings; in the illustrated example one of said shafts 126 carries a sprocket pinion 127 connected by means of a sprocket chain 128 with a sprocket pinion 129 secured upon the shaft 60 whereby said dryer belt is in driving connection with the motor or other power plant through the previously described gearing which includes the elliptical gears 57 and 58. The upper run of the dryer belt 124 is supported against sagging by means of closely adjacent supporting rolls 130 journalled on the frame 25 as shown in Figs. 1 and 2; a suitable tension device 131 may engage the lower run of the belt 124 for maintaining the latter under the proper tension. The dryer belt 124 is not heated, although it may be if this is desirable for any reason; in the present instance the term "dryer" is employed to designate a device arranged to maintain the glued closing

flaps of the carton securely in position under pressure until the glue has been sufficiently absorbed by the carton material to fix said flaps securely in place; the drying operation, 5 in other words, is a matter of absorption of moisture from the glue into the carton material rather than an actual evaporation of moisture by heat. A discharge belt 132 is located at a downward inclination to the dryer belt 124 as shown in Figs. 1 and 9, and passes over rollers 133 carried by shafts 134 journaled upon a sub-frame 135 which projects from and is secured to that part of the main frame 25 on which the dryer belt 124 is 10 mounted. If desired, or found necessary, guard rails 135^a may be fixed upon the sub-frame 135 at opposite sides of the belt 132 to prevent the cartons *b* or their equivalent from leaving the belt 132 and to guide them 15 in their travel to the discharge end thereof. The discharge belt 132 is driven in any convenient manner as by having one of the shafts 134 provided with a pinion 136 in mesh with a pinion 137 fixed upon a stub-shaft 138 rotatably mounted upon the sub-frame 135; the stub-shaft 138 in turn carries a sprocket 139 connected by means of a sprocket chain 140 with a sprocket 141 fastened upon the carrier chain shaft 28 as shown in Figs. 1 and 20 25 9. If, as in the illustrated example, the receiving end of the discharge belt 132 is located in spaced relation to the delivery end of the dryer belt 124, the machine preferably includes a transfer device whereby the filled 30 cartons, or their equivalent, are transferred from the dryer belt 124 to the discharge belt 132 in a manner to prevent dropping of said cartons. As shown in the drawings this device comprises a carton retaining member 142 35 fixed upon a shaft 143 journaled in brackets 144 which, for instance, form part of the sub-frame 135 as illustrated in Figs. 1 and 9, said retaining member 142 being held in and returned to the normal receiving position, 40 shown by full lines in Fig. 1, and by dotted lines in Fig. 9, by means of a spring 145; the latter has its one end secured to a pin 146 on the frame 25 and its other end fastened to an arm 147 fixed upon the shaft 143. 45 50 In packing certain commodities, such as the shredded whole wheat biscuits *a*, it is desirable to separate adjacent biscuits or adjacent layers of biscuits or their equivalent, by means of cards *c* of paper, cardboard or other suitable material dimensioned to fit the interior of the cartons *b* or equivalent containers. In the machine, as illustrated in the drawings, stacks of such cards *c* are contained in stationary magazines 148 of suitable form located upon the frame 25 within easy reaching distance of the operators at the several stations A, B, C, D and E, as shown in Figs. 1 and 2; in the preferred arrangement the cards *c* are successively removable from the bottom of the stacks through discharge open-

ings 149 provided adjacent to the bottoms 150 of said magazines as illustrated in Fig. 11. To facilitate the successive removal of the terminal cards from the bottoms of the stacks, each magazine includes suction means whereby said terminal cards are selectively adjusted and held in positions ready for easy removal by the operators at the proper time. Each suction means, in its illustrated form, 70 comprises a suction cup 151 carried by a lever 152 fixed upon a shaft 153 journalled in brackets 154 at the lower end of each magazine in operative relation to the aforesaid discharge openings 149 as shown in Fig. 11. The shafts 153 are each provided with an arm 155 connected by means of links 156 with levers 157 as indicated in Fig. 11, said levers 157 being all located upon a control shaft 158 journalled in suitable bearings 159 suitably secured upon the main frame 25. The control shaft 158 has fixed thereon, at one end, a control lever 160 connected by means of a connecting rod or link 161 with an arm 162 pivoted at 163 upon the frame 25; at its free end the arm 162 is provided with a roller 164 arranged for engagement with a suitable cam 165 fixed upon the shaft 28 as illustrated in Fig. 9. Preferably the arm 162 is provided with a plurality of apertures 166 for the reception of the one end of the rod 161 to vary its point of connection with said arm 162 whereby the operative movements of the suction cups 151 may be varied in extent at will. The suction cups 151 are individually connected by means of suction hose 167 with a common suction manifold 168 in which suction is continuously maintained throughout a given period of operation by any conventional form of suction producing means with which said suction manifold 168 is suitably connected. 80 85 90 95 100 105 110 115 120 125

If the nature of the units or other material being packed makes it desirable, the machine may further include a discharge chute 169 extending lengthwise of the machine at an inclination beneath the upper run of the carrier chains 26 and preferably above the lower run thereof; as shown in Fig. 10, the chute 169 may be suitably secured at 170 to the upper and lower guides 32 so as to extend between the same at an angle. The lower runs of the carrier chains 26, and associated mechanism, is thus protected against crumbs or other residue of material which may develop in the handling of the units, such as the biscuits *a* or other material being packed, and as a result is prevented from becoming clogged or otherwise rendered deficient in operation; as clearly shown in Fig. 10, the chute 169 will deflect the crumbs or their equivalent out of the machine in the manner indicated by the arrows. 130

The following description sets forth the operation of the machine in its illustrated form as used for packing shredded whole wheat

biscuits, it being understood that the operation will be substantially the same regardless of the material being packed, although it may vary in details to meet the requirements of the particular type of material being packed. In practice, the biscuits *a* are delivered to the machine in any convenient manner and from any suitable source of supply, and as shown may be contained in predetermined numbers upon pans *P* which, in such case, are carried by the conveyor belt 78, for instance, from right to left. As a result of this, a given pan of biscuits will be carried successively to the stations A, B, C, D and E. At the same time, the carrier chains 26 will be correspondingly actuated and accordingly will cause the pockets 33 and retaining forms 35 to move to the same stations successively. As the carrier chains 26 travel in the indicated manner, the rollers 42, by engagement with the pocket opening cam 43, will gradually swing the pockets 33 from an upright position within the retaining forms 35 to gradually more inclined positions. In their passage along the cam 43, the action of the latter will pivotally swing the levers 39 and cause the pins 38 to shift lengthwise of the slots 37 and to thereby exert a force upon the arms 36 tending to pivotally swing the pockets 33 to their inclined positions, as is clearly shown in Fig. 11. By the time the pockets reach the station A the fully inclined position of 53° more or less will have been reached and the rollers 42 will by this time be in rolling engagement with the rod 45 to fix said pockets in said inclined positions. As clearly shown in Figs. 3 and 4, the open pockets thus extend toward the operators seated on the chairs 56 at the respective stations A-E and within easy reach of such operators, and in cooperative proximity to the supply of biscuits *a*. As a pocket 33 reaches the operator at station A, said operator places two biscuits *a* within said pocket and upon the ejector plate 48 therein. By reference to Fig. 11 it will be seen that the ejector plate 48 forms an acute angle with the pocket 33. This arrangement reduces the apparent width of the space occupied by the biscuits while contained in the pocket and thus allows the biscuits to fit the available space between a given pocket 33 and the cooperative retaining form 35, without crushing. In packing the biscuits *a*, it is customary to place cards *c* of suitable material, such as paper or cardboard, between the respective layers of two biscuits. The operator at station A having placed the first two biscuits *a* upon the ejector plate 48 withdraws a card *c* from the lower end of the stack in the magazine 148 which is nearest to her and places this card upon the two first biscuits. At the stage when a card *c* is required, the terminal cards at the lower ends of the respective stacks will be drawn downwardly

by the action of the suction cups 151 and their associated parts to the position indicated in Fig. 11. This will be brought about by the action of the cam 165 on the arm 162, which at the proper moment is operated to rock the shaft 158 in a direction to cause a push to be exerted by the levers 157, links 156 and arms 155 to thereby rock the shafts 153 and swing the arms 152 and suction cups 151 to the position shown in Fig. 11. After the card *c* has been withdrawn, the suction means is operated to return the suction cups 151 into engagement with the succeeding card *c* which now becomes the terminal card at the lower end of each stack in the magazines 148; as suction is continuously maintained in the suction manifold 168 throughout a given period of operation of the machine, the suction cups 151 will immediately be in suction connection with said terminal card, ready for the next operation by the cam 165 and its associated elements. As the pocket in which the two biscuits *a* have been placed reaches the operator at the station B, she in turn places two more biscuits *a* and a card *c* in the pocket. This operation is repeated by each operator at the respective stations so that by the time the pocket in question has reached the station E it contains the predetermined number of biscuits or other quantity of material which is to be packed in a carton *b* or its equivalent. Successive pockets are correspondingly filled with biscuits *a* and intervening cards *c* throughout a given operative period of the machine.

After the pockets have been thus filled with the predetermined supply of biscuits they will be carried along by the carrier chains 26 and the rollers 42 will pass from the rod 45 and will ride up on the pocket closing cam 44 which will act upon the rollers 42, the levers 39 and members 36 in a manner to swing said pockets into their upright positions in which they are housed within the retaining forms 35. At this stage the predetermined numbers of biscuits *a* are thus located within the tubular containers formed by the pockets 33 and retaining forms 35, and rest in double columns with intervening cards *c* upon the ejector plates 48. In the continued operation of the machine, the rollers 42 travel along the rod 46 so that the pockets 33 are positively fixed in their closed positions within the retaining forms 35. The latter, with the pockets 33 housed therein, pass between the form closing rolls 33^a and are then ready to receive the cartons *b*. As the station F is reached, the operator, seated on the chair 56 thereat, takes successive cartons *b* from the supply contained in the magazine 171 located at the station F, and after bringing said cartons *b* to their unfolded tubular condition, telescopically fits the same upon the combined retaining forms 35 and pockets 33 in an inverted condition. Suitable stops

172 are preferably provided upon the retaining forms 35 to properly position the cartons *b* in the intended location on each cooperating retaining form 35 and pocket 33, as shown in Fig. 8.

5 As the cartons *b* continue along on the pockets and retaining forms, the rear flaps *b*1 engage the flap retainer 99, after which the tucker 89 is actuated to fold the rear flap *b*2 into place, the folded flaps *b*1 and *b*2 being held in their folded positions by the action of the flap retainer 99 along which they travel in the continued operation of the machine, as shown in Fig. 8.

15 As the flaps *b*1 and *b*2 are folded in the indicated manner, the cartons *b* will gradually approach the glue rolls 103. As this occurs, the side flaps *b*3 are engaged by the flap guides 100, by which said side flaps *b*3 are distended, as shown in Fig. 16. The side flaps *b*3 are thus spread, far apart into an approximately flat position and therefore readily enter the spaces between the glue rolls 103 and the gluing bars 102 which press said flaps *b*3 firmly against the glue rolls 103 so as to secure full contact of the flaps with said rolls, which accordingly provide said side flaps with coatings of glue. The cartons *b* with the front and rear flaps folded inwardly and the side flaps *b*3 distended outwardly and coated with adhesive, travel in a curved path as shown in Fig. 8, during which the rolls 42 pass along the curved rod 46^a, which comprises a continuation of the bar 46. As the carrier chains 26 resume a straight line motion in a return direction, the cartons are carried to the first folding device 123 which gives the one side flap *b*3 a preliminary inward fold, as shown in Fig. 18, after which the cooperating folding member 107^a is actuated to complete the folding of this side flap *b*3 as indicated in Fig. 19 and to bring the same into surface contact with the previously folded front and rear flaps *b*1 and *b*2, to which said side flap adheres by the action of the adhesive. The folding member 107 is then moved in a return direction, and at the same time, the other side flap *b*3 is given a preliminary inward fold, as indicated in Fig. 20, and the second folding member 107^a is actuated to complete the inward folding of the second side flap *b*3 to the position as shown in Fig. 21, in which said second side flap *b*3 adheres to the previously folded first side flap *b*3; in this way the bottoms of the cartons *b* are formed.

Leaving the folding means just described, the sealed cartons *b* pass to the dryer belt 124, as shown in Fig. 8, the upper run of which 60 travels in parallel relation to and at the same speed as the carrier chains 26 and holds the flaps in their folded position under pressure until the glue or other adhesive is dried sufficiently to firmly secure the flaps in place; it 65 will be understood that the dryer belt 124 is

of such length that it will exert its influence upon the folded flaps for a period of time sufficient to bring about the necessary drying of the adhesive. As the cartons which, it will be noted, are now in a proper upright position, leave the dryer belt 124, they engage the member 142 and are gradually lowered thereby against the tension of the spring 145 to the discharge belt 132 which is located at a downward inclination, as shown in Fig. 9. 70 At this stage the rollers 53, located upon the pockets 33, engage the ejector cam 54 and as they travel along the same, shift the carriers 49 lengthwise of the slots 51 and thereby move the ejector plates 48 toward the open ends of the containers formed by the combined pockets 33 and retaining forms 35. In this way, the stacked biscuits *a* with the intervening cards *c* are ejected from the aforesaid containers, coincidentally with the removal of the cartons *b*, which move downwardly by gravity. At this stage of the operations, the rollers 42 travel along the rod 47 so that the pockets 33 are securely held within the retaining forms 35, as is clearly 80 shown in Fig. 9. The filled cartons *b* being finally completely disengaged from the combined pockets and retaining forms are carried along by the discharge belt 132 and are either manually removed therefrom or delivered thereby to a cooperating conveyor, by which said filled cartons may be carried away to have the upper flaps properly closed. 85 As soon as the filled cartons have been thus disengaged, the rolls 53 will pass into engagement with the cam 55 which acts upon said rolls 53 and the slides 49 in a manner to return the ejector plates 48 to their initial positions; these operations take place as the pockets 33 and retaining forms 35, still in 90 closed combination with each other, pass in a curved path toward the upper run of the carrier chains 26, after which the foregoing operations are repeated.

It will be noted that while the biscuits 100 occupy an inclined position, while the pockets and retaining forms travel with the upper run of the carrier chains 26, said biscuits, after having been acted upon by the ejector, are liberated from the confined space between 105 the pockets 33 and retaining forms 35 and thereafter lie flat upon the bottoms of the cartons *b*. In assuming this flat position, the effective width of space occupied by the biscuits is such that they substantially fill the 110 interiors of the cartons.

As has been stated, biscuits are placed in the pockets and retaining forms in somewhat distorted units, that is, each biscuit is angularly disposed with respect to the retaining 115 walls, and the ejector forms one end or closure for the pocket and retaining form. It is obvious that by varying the cam or its high portions, the volumetric capacity of the pockets and retaining forms can be varied, as the 120 125 130

- roller attached to the ejector 53, will in combination with its cam act to limit the length of the complete form. This will be evident from an inspection of Figures 10, 11 and 12.
- 5 Similarly, if desired, the space between the pockets 33 and retaining form 35 might be varied in accordance with the type of material to be packed, that is when one material is being handled the pockets 33 and retaining forms 35 will be mounted upon a carrier 30 in such a manner as to space them a greater or lesser distance apart than similar retaining forms, or pockets mounted upon a carrier 30, for use when a different material is to be 10 packaged. The stops 172, as shown in Figures 10, 11 and 12, are adjustable and provide a means for varying the volumetric capacity by limiting the telescoping insertion of the complete form into its carton.
- 15 It will be noted, as shown in Fig. 2, that the train of gearing whereby the carrier chains 26 are actuated, includes the elliptical gears 57 and 58. The arrangement of these gears 57-58 is such that the pockets 33 will be 20 moving very slowly, while the operators at the stations A-E are placing the biscuits *a* therein and travel at a much greater speed when the pockets are shifted from one station to the next. The operation of the machine is 25 thus of maximum efficiency and its output is materially increased, without requiring the operators to work at an uncomfortable speed, the latter having ample time in which to insert the biscuits in the desired manner,
- 30 35 into the pockets. Because of the fact that these travelling elements of the machine which cooperate with the carrier chains 26 and the pockets 33 and retaining forms 35 carried thereby are driven by the same train of gears, 40 the operation of these elements will be in exact mechanical accord with the operation of said pockets and retaining forms.
- As previously stated, the selection of individual cards *c* from the lower ends of the 45 stacks contained in the magazines 148 is facilitated by the provision of the suction mechanism which includes the suction cups 151 and their associated elements. At each revolution of the card delivering cam 165, the 50 vacuum cups 151 are pressed against the bottom card *c* and are caused to adhere thereto by the suction created in the suction manifold 168. At the proper times the suction cups 55 151 are actuated in the manner previously described to draw down the bottom card *c* to the position indicated in Fig. 11, in which the individual cards are readily withdrawn from the magazines by the operators. The 60 next cycle of operation causes the suction cups 151 to be again pressed against the bottom cards in the magazines and to draw them downwardly, ready for use when required.
- In the present example of the invention the 65 packages, or in other words, the cartons *b*, contain twelve biscuits *a*, arranged in six lay-

ers of two biscuits each, the layers being separated by the cards *c*, it being understood that the number of biscuits mentioned is merely illustrative as any predetermined number of biscuits may be packed and the number of packing stations may be varied as desired to accommodate the desired predetermined number of biscuits inserted in the form.

With the novel machine, units of material such as the biscuits *a* may be expeditiously 70 arranged in an orderly fashion within the cartons or their equivalent, without requiring any particular skill on the part of the operators, and are arranged in an orderly fashion, prior to the introduction into said cartons, with a minimum of effort. The novel machine also permits the mechanical packing of bulk materials in an efficient manner, it being understood that the pockets 33 and retaining forms 35 will be provided in a form 75 consistent with the requirements of the material being packed and that, if necessary, other parts of the mechanisms will be accordingly arranged. In any case the machine increases the packing speed, and the consequent output 80 of a given plant, to a material degree, without the necessity for any complicated mechanical arrangements or highly developed skill on the part of the operators.

Various changes in the specific forms shown 85 and described may be made within the scope of the claims without departing from the spirit of the invention.

We claim:

1. The method of packing materials, which 100 consists in confining the material in predetermined quantities, by fabricating a form thereabout, then fabricating a container about such confined material in spaced relation thereto and subsequently expelling the confined material and container simultaneously to transfer the material to said container.

2. The method of packing materials, which 105 consists in confining a predetermined quantity of material by fabricating a hollow form thereabout, then fabricating a container about such form in spaced relation to said material and coincidentally removing the material and container from said form to transfer said material to said container.

3. The method of packing units of material, which consists in confining a predetermined number of such units by fabricating a form thereabout, then fabricating a carton about such confined units in spaced relation 120 to said units and coincidentally expelling the confined units and the carton to transfer said units to said carton.

4. The method of packing units of material, which consists in collecting a predetermined number of units, confining said collection of units, by fabricating a form thereabout then fabricating a carton about such confined units in spaced relation to said units and simultaneously expelling the confined 125 units 130

- units and the carton to transfer said units to said carton.
5. In a packing machine, the combination of a confining device for confining a predetermined quantity of material, comprising separable members, means to position said members to receive said material, means to position said members to retain said material therein, said confining device in addition constituting a form for a container, said container and quantity of material being simultaneously removable from said confining device to transfer the material to the container. 70
10. In a packing machine, the combination of a hollow form adapted to receive the material to be packed and constituting a measuring device, formed of separable members, means to position said members to receive said material, means to position said members to retain said material therein, said form being arranged to removably receive a container, and means for simultaneously ejecting the material and container from said form to transfer the material to said container. 80
15. In a packing machine, the combination of a mechanically operated hollow receiver, adapted to receive a predetermined quantity of material and said receiver comprising separable members, means to position said members to receive said material, means to position said members to retain said material therein, said receiver constituting a form on which a container for said material is subsequently fabricated. 90
20. In a packing machine, the combination of a hollow form adapted to contain a predetermined quantity of material and composed of a plurality of relatively movable elements, means to position said elements to receive said material, means to position said elements to retain said material therein and means for mechanically controlling the operation of said elements. 95
25. In a packing machine, the combination of a hollow form for containing the material to be packed and adapted to telescopically receive a container, and comprising separable members, means to position said members to receive said material, means to position said members to retain said material therein and means for varying the volumetric capacity of the hollow form whereby the latter comprises a container supporting means and a measuring device. 100
30. In a packing machine, the combination of a receptacle for a predetermined quantity of material, said receptacle constituting a form for receiving the container for the material, and comprising separable members, means to position said members to receive said material, means to position said members to retain said material therein and means for forming the bottom of said container while it is supported on said receptacle. 105
35. In a packing machine, the combination of a hollow form adapted to receive a predetermined quantity of material and to constitute a support for a container for said material, and comprising separable members, means to position said members to receive said material, means to position said members to retain said material therein and means for applying force from the exterior of said form to discharge said container and material from said form. 110
40. In a packing machine, the combination of a travelling receptacle adapted to support a container and including a movable pocket adapted to receive material, means for adjusting said pocket to receiving position, means for adjusting said pocket to a closed confining position, and means for coincidentally ejecting the container and material from said receptacle to transfer the material to said container. 115
45. In a packing machine, the combination of a receptacle adapted to receive material and thereafter to telescopically receive a carton for said material, and comprising separable members, means to position said members to receive said material, means to position said members to retain said material therein, means to move said receptacle from material receiving position to a discharging position and means for discharging the filled carton from the machine. 120
50. In a machine for packing units, the combination of means including a pocket and a retaining form cooperative therewith for confining assembled units in groups for retaining said groups in confined position and for supporting cartons to receive such groups, and means for discharging said units into said cartons in a manner to substantially fill the same when said cartons are disengaged from said unit assembling means. 125
55. In a packing machine, the combination of a mechanically operated form for receiving the material and a container therefor, said form including a receiving pocket and a retaining form movable into cooperative relation with said pocket and means for subsequently transferring said material to the carton coincidentally with the transfer of the carton from the form. 130
60. In a packing machine, the combination of a traveling carrier, a plurality of receiving forms mounted on said carrier and adapted to receive and retain predetermined quantities of material therein and to telescopically receive cartons for subsequently containing said material, means for closing one end of each carton after its form has been loaded with material, and means for coincidentally discharging said cartons and material from said forms. 135
65. In a packing machine, the combination of a travelling carrier, a plurality of retaining forms on said carrier, a plurality of pockets cooperating with said retaining forms to

provide receptacles for the material, means for adjusting said pockets to open receiving positions, means for adjusting said pockets to closed positions, and means for coincidentally transferring the material and the cartons from said receptacles.

18. In a packing machine, the combination of an endless travelling carrier, a plurality of retaining forms on said carrier, a plurality of pockets pivotally mounted in cooperative relation to said retaining forms and adapted to form receptacles therewith for receiving quantities of material, means in operative relation to the upper run of said carrier for adjusting said pockets to open receiving positions, means in operative relation to the upper run of said carrier for shifting said pockets to closed positions to form with said retaining forms containers for confining said material and for telescopically receiving cartons, means for closing one end of said cartons, an endless belt in operative relation to the lower run of said carrier for exerting pressure on said closed ends of the cartons, a discharge belt in operative relation to the lower run of said carrier, ejector means for ejecting the material from said receptacles coincidentally with the removal of the cartons therefrom to the discharge belt, and means for restoring said ejector means to the initial positions.

19. In a packing machine, a plurality of filling stations, an endless travelling conveyor having its upper run arranged to travel adjacent to said filling stations, a plurality of retaining forms on said carrier, a plurality of pockets pivotally associated with said retaining forms, systems of interconnected levers associated with said pockets, means in operative relation to the upper run of said carrier cooperating with said lever systems to adjust said pockets to open receiving positions and to maintain them therein in proximity to said filling stations, means effective subsequently on said lever systems to adjust said pockets to closed positions to form with said retaining forms containers adapted to telescopically receive cartons, including flaps, means for folding and pasting flaps at one end of said cartons to form bottoms therefor, a dryer belt adjacent to the lower run of said carrier arranged to exert pressure on said pasted and folded flaps to fix them in position, a discharge belt, ejector means adapted to discharge the material from said receptacles to said cartons and to discharge said filled cartons to the discharge belt, and means for restoring said ejector means to the initial position.

20. In a packing machine for units of material, the combination of an endless carrier, a train of gearing including elliptical gears for operating said carrier alternately at higher and lower speeds, a plurality of retaining forms on said carrier, a plurality of pockets

pivottally associated with said retaining forms and adapted to form therewith receptacles for receiving a predetermined number of said units, ejector plates slidably mounted on said pockets and forming acute angles therewith for temporarily supporting said units in distorted positions, a pocket-opening cam in operative relation to the upper run of said carrier for adjusting said pockets to open receiving positions, means for maintaining said pockets in said open positions for predetermined periods of time, a pocket closing cam in operative relation to the upper run of the carrier for adjusting said packages to closed positions to form said receptacles, the latter being adapted to telescopically receive cartons provided with flaps, folding and gumming means for folding and pasting said flaps to form bottoms for said cartons, a dryer belt in operative relation to the lower run of said carrier for exerting a pressure on said folded and pasted flaps for a predetermined period, an inclined discharge belt located in spaced receiving relation to said dryer belt, means for transferring the cartons from said dryer belt to said discharge belt, an ejector operating cam in operative relation to said discharge belt for transferring the material and the cartons from the receptacles to said discharge belt, and a cam for restoring said ejector plates to their initial positions.

21. In a packing machine for packing units of material in cartons in superposed layers separated by cards, the combination of multi-part travelling forms adapted to receive predetermined numbers of said units and cards, means to separate said parts for reception of said units and cards and to thereafter return said parts, magazines containing stacks of cards and suction means for separating the terminal cards of said stacks therefrom, and means to discharge said units and cards from the forms into said cartons.

22. In a packing machine for units of material adapted to be contained in cartons in superposed layers separated by cards, the combination of multi-part travelling receptacles adapted to receive the predetermined numbers of such units and cards, means to separate said parts for reception of said units and cards and to thereafter return said parts, magazines containing stacks of said cards and provided with discharge openings at their lower ends, suction cups connected with a source of suction and adapted to exert a suction effect upon the terminal cards at the lower ends of said stacks, pivoted arms carrying said suction cups, and means for pivotally actuating said arms to cause said suction cups to bend the terminal cards away from the remainder of the stack, and means to discharge said units and cards from the forms into said cartons.

23. In a packing machine of the kind de-

- scribed, a plurality of travelling forms adapted to receive and retain predetermined quantities of material therein and to receive cartons including end flaps, means for applying an adhesive to some of said flaps, folding devices for imparting a preliminary fold to said last named flaps and inversely movable folding members for successively folding said flaps to their final positions, and to discharge 10 said material into the carton after the flaps have been folded.
24. In a packing machine of the kind described, a plurality of travelling forms adapted to receive and retain predetermined quantities of material therein and to receive cartons including end flaps, means for applying an adhesive to some of said flaps, inversely 15 slideable folding members for successively folding said flaps to their final positions, bell- 20 crank levers connected with said folding members and connected cams for actuating said bell-crank levers to operate said folding-members inversely, and to discharge said material into the carton after the flaps have 25 been folded.
25. In a packing machine of the kind described, a plurality of travelling forms adapted to receive and retain predetermined quantities of material therein and to receive cartons including front and rear flaps and side 30 flaps, means for successively folding said end flaps inwardly, means for spreading said side flaps outwardly to extended positions, gluing means for applying glue to said distended 35 side flaps, folding devices for successively imparting preliminary inward folds to said glued side flaps, inversely movable folding members for successively folding said side flaps to their final folded positions, mechanism 40 for inversely operating said folding members, and travelling means for exerting pressure upon said folding flaps, and to discharge said material into the carton after the flaps have been folded.
26. The method of packing materials which 45 consists in supplying predetermined quantity of material, in then confining the material therein, by fabricating a form thereabout, in subsequently fabricating a container about the confined material and in spaced relation thereto, and in subsequently expelling the confined material and container coincidentally, thereby to transfer the material to the 50 container simultaneously with said expulsion.
27. The method of packing units of material which consists in supplying predetermined number of such units, inserting separators between groups of units, then confining 55 said separated groups therein by fabricating a form thereabout, in subsequently fabricating a container about the confined units and in spaced relation thereto and in subsequently expelling the confined units and container coincidentally, thereby to transfer
- the units to the container mechanism with said expulsion.
28. In a packing machine the combination of a traveling receptacle, including a movable pocket adapted to receive material, means for adjusting the pocket to receiving position, means for adjusting said pocket to a closed confining position, means to guide said receptacle through a horizontal plane while traveling in its receiving position, and means for completely reversing the receptacle from its closed confined position whereby the container and material may be ejected from said receptacle.
29. In a packing machine the combination of a traveling receptacle adapted to support a container and comprising a movable conveyor having a pocket member fixed in substantially perpendicular position thereon, and adapted to receive material, a confining member 80 movably mounted thereon and effective to close said pocket, means for adjusting said pocket and confining member to receiving position, means for adjusting said members to a closed confining position, and means 85 for coincidentally ejecting the container and material from said receptacle to transfer the material to said container.
30. In a packing machine the combination of a traveling receptacle adapted to support a container and comprising a movable conveyor having a pocket member fixed in substantially perpendicular position thereon, and adapted to receive material, a cam actuated confining member movably mounted 90 thereon and effective to close said pocket, said members being substantially U-shaped in cross section and telescopically related to each other, means for adjusting said members to a closed confining position, and means for coincidentally ejecting the container and material from said receptacle to transfer the material to said container.
31. In a packing machine the combination, of a traveling receptacle adapted to receive material and comprising a conveyor having mounted thereon a pair of members effective to form a material receiving pocket open at one end, said members being relatively movable, cam means to effect said relative movement, means for adjusting said receptacle to receiving position, means for adjusting said receptacle to a closed confining position, and means for ejecting the material 110 from said receptacle into a container.
32. In a packing machine the combination, of a traveling receptacle adapted to receive material and comprising a conveyor having mounted thereon a pair of members effective to form a material receiving pocket open at one end, said members being relatively movable, cam means to effect said relative movement, means for adjusting said receptacle to receiving position, means for adjusting said receptacle to a closed confining position,

- means for fabricating a container about said receptacle when it is in closed confining position, and means for simultaneously expelling the container and material from the receptacle to transfer the material to the container.
33. In a packing machine the combination, of an endless traveling carrier, a plurality of retaining forms on said carrier, a plurality of pockets pivotally mounted in co-operative relation to said retaining forms and adapted to form receptacles therewith for receiving quantities of material, means for adjusting said pockets to open receiving positions, means for shifting said pockets to closed positions to form with said retaining forms containers for confining said material and for telescopically receiving cartons, means for closing one end of said carton, and cam actuated ejector means for ejecting the material from said receptacles coincidentally with the removal of the cartons therefrom.
34. In a packing machine the combination, of an endless traveling carrier, a plurality of retaining forms on said carrier, a plurality of pockets pivotally mounted in co-operative relation to said retaining forms and adapted to form receptacles therewith for receiving quantities of material, means for adjusting said pockets to open receiving positions, means for shifting said pockets to closed positions to form with said retaining forms containers for confining said material and for telescopically receiving cartons, means for closing one end of each carton, cam actuated ejector means for ejecting the material from said receptacles coincidentally with the removal of the cartons therefrom, and cam actuated means for restoring said ejector means to the initial position.
35. In a packing machine the combination, of a traveling receptacle adapted to receive material and to telescopically receive a carton for said material, an endless conveyor upon which said receptacle is mounted, means for discharging filled cartons from the machine, and a deflector mounted between the upper and lower runs of said conveyor for directing spilled residue away from the moving parts of the machine.
36. In a packing machine the combination, of an endless traveling carrier, a plurality of retaining forms on said carrier, a plurality of stations spaced along the path of travel of said carrier, means to increase the rate of speed of the carrier as the retaining forms move from station to station and to decrease the rate of speed as said forms pass a station, whereby said forms may be partially filled with material to be packed, at each station, said retaining forms being adapted to telescopically support a carton, and ejector means for coincidentally ejecting the carton and the material from the form to transfer the material to the carton.

37. In a packing machine the combination, of an endless traveling carrier, a plurality of retaining forms on said carrier, a plurality of stations spaced along the path of travel of said carrier, means comprising a pair of elliptical driving gears to increase the rate of speed of the carrier as the retaining forms move from station to station and to decrease the rate of speed as said forms pass a station, whereby said forms may be partially filled with material to be packed, at each station, said retaining forms being adapted to telescopically support a carton, and ejector means for coincidentally ejecting the carton and the material from the form to transfer the material to the carton.

38. In a packing machine the combination, of an endless traveling carrier, a plurality of retaining forms on said carrier, a plurality of stations spaced along the path of travel of said carrier, means to increase the rate of speed of the carrier as the retaining forms move from station to station and to decrease the rate of speed as said forms pass a station, whereby said forms may be partially filled with material to be packed, at each station, said retaining forms being adapted to telescopically support a carton, means for closing one end of the carton, an endless belt in operative relation to the lower run of said carrier for exerting pressure on the closed end of the carton as the carton reaches said lower run, and ejector means for coincidentally ejecting the carton and the material from the form to transfer the material to the carton.

39. In a packing machine the combination, of an endless traveling carrier, a plurality of retaining forms on said carrier, a plurality of stations spaced along the path of travel of said carrier, means comprising a pair of elliptical driving gears to increase the rate of speed of the carrier as the retaining forms move from station to station and to decrease the rate of speed as said forms pass a station, whereby said forms may be partially filled with material to be packed, at each station, said retaining forms being adapted to telescopically support a carton, means for closing one end of the carton, an endless belt in operative relation to the lower run of said carrier for exerting pressure on the closed end of the carton as the carton reaches said lower run, and ejector means for coincidentally ejecting the carton and the material from the form to transfer the material to the carton.

MORRIS M. RAYMER.
